UNITED STATES PATENT OFFICE.

CHARLES RODERICK, OF WOODSTOCK, ILLINOIS, ASSIGNOR TO THE
OLIVER TYPEWRITER COMPANY, OF CHICAGO, ILLINOIS, A COR-
PORATION OF ILLINOIS.

LATERAL LOCK FOR CARRIAGE SHIFT-FRAMES.

No. 829,089.

Specification of Letters Patent.

Patented Aug. 21, 1906.

Application filed November 4, 1905. Serial No. 285,863.

To all whom it may concern:

Be it known that I, CHARLES RODERICK, a citizen of the United States, residing at Woodstock, in the county of McHenry and State of Illinois, have invented certain new and useful Improvements in Lateral Locks for Carriage Shift-Frames; and I do hereby declare that the following is a full, clear, and exact description thereof, reference being had to the accompanying drawings, and to the letters of reference marked thereon, which form a part of this specification.

This invention relates to a novel construction in type-writing machines of that class in which the type-bars are provided each with a plurality of types and the paper-carriage is supported and has endwise movement upon a shift-frame, which shift-frame is moved or shifted on the main frame of the machine to bring the platen in position for the action on the paper of either of the types of the type-bars.

The invention relates more especially to a novel means of locking or holding from vibratory movement the shift-frame when the latter reaches the limit or end of its shifting movement in each direction.

My invention is shown in the accompanying drawings as applied to what is known as an "Oliver" type-writing machine; but the features of improvements embodying the invention may be used in connection with typewriters of other kinds that are provided with a platen-shift device.

As shown in the said drawings, Figure 1 is a view in side elevation of the rear end of a carriage shift-frame of an Oliver type-writing machine with the guide rod or stem thereon and the standards on the machine base-plate by which said guide rod or stem is supported. Fig. 2 is a plan view of the parts shown in Fig. 1. Fig. 3 is a vertical section taken upon line 3-3 of Fig. 1. Fig. 4 is a perspective view of one of the tapered blocks on the said rod or stem.

As shown in the drawings, A indicates the base-plate of the machine; B, the rear portion of the shift-frame, and C the guide rod or stem, which is attached to the rear end of the shift-frame and has endwise movement with the shift-frame as the latter is shifted forwardly and backwardly to bring the platen

in position for the action thereon of either one of the types on the type-bars.

D indicates the standard which is attached to and rises from the base-plate A and which is vertically-slotted in its upper part for the passage of the guide-rod and to receive a guide-roller D', which is journaled in the standard and on which rests the rear end of the guide-rod.

D² designates the second standard on the base-plate, having an open notch at its upper end through which the guide-rod C passes.

c c' are stops on the guide-rod located at opposite sides of the standard D² and adapted for contact therewith in such manner as to limit the forward and rearward movement of the guide-rod and the shift-frame, to which it is attached. Said guide-rod is shown as 70 screw-threaded in its part adjacent to the standard D² and the stops c c' as having the form of nuts applied to the screw-threaded portion of said rod.

The standard D extends above the guide-rod C, and to its upper end is attached a horizontal plate E, which is attached to the lateral parts of the standard by means of screws e e. In said plate E centrally over the guide-rod C is located a set-screw e', the lower end 80 of which is located closely adjacent to the guide-rod and which serves to hold said guide-rod from rising. So far as described the parts are constructed in the same manner as the corresponding parts of the Oliver type-writer as heretofore constructed.

Now referring to the novel features constituting my invention, the carriage shift-frame is provided with oppositely-inclined or oblique contact-surfaces and the machine-frame 90 with like correspondingly-inclined or oblique contact-surfaces, which surfaces in the shift-frame and machine-frame are located in position for contact with each other at each limit of the throw of the shift-frame. As 95 shown in the drawings, the oblique surfaces on the shift-frame are formed by the side-faces of tapered blocks F F', attached to the guide-rod C at the front and rear of the standard D, while the inclined surfaces on 100 the machine-frame are formed by the outwardly-divergent sides of oppositely-facing tapered notches E' E² in the plate E. Said plate E is extended forwardly and rearwardly

from the standard D, the notches E' E² being formed in the marginal parts of the plate above said rod C. The blocks F F' are tapered to correspond with the notches and 5 are attached to the rod C by means of integral split rings F² F³, which are clamped about the rod by clamp-screws f f'. The oblique side faces of the said tapered blocks F F' are located in position for contact with the 10 correspondingly-inclined side walls of the notches E' E² at each limit of the movement or throw of the shift-frame, the notches and blocks being arranged to come in contact with each other at the time one of the stops c 15 or c' on the stem strikes the standard D². Said stops serve to accurately determine the position of the platen relatively to the types, while the interfitting engagement of the notches and blocks hold the shift-frame from 20 vibratory movement.

The result of the construction described is that while the stem is adapted to slide or move freely in the guide-standard D in the endwise movement of the said stem, yet at 25 each limit of such endwise movement the stem is positively locked against any lateral shifting or vibratory movement by contact of the inclined surfaces of the blocks with the inclined surfaces of the notches. In other 30 words, the oblique or inclined surfaces on the shift-frame stem and on the standard D by coming into interfitting contact with each other at each limit of the movement of the shift-frame positively lock or hold said 35 shift-frame from lateral vibration or movement. This is a matter of considerable importance, because the impact of the types upon the platen takes place immediately after the platen has been shifted to the forward or rearward limit of its throw and any displacement of the shift-frame which might take place at that time will result in the making of imperfect impressions.

While I have shown the contacting parts 45 having the tapered or oblique surfaces referred to as applied to the guide rod or stem on the shift-frame and to the guide-standard of an "Oliver" type-writing machine, yet the features of construction embodying the invention may be otherwise applied to the shift-frame and stationary part of the machine, and such features may be employed in connection with the shift-frame of machines other than the said "Oliver" type-writer. 50 Moreover, the features constituting my invention may be applied to a single-shift machine as well as to a double-shift machine. It will therefore be understood that I do not wish to be limited to the details of construction 55 and arrangement of the parts illustrated in the accompanying drawings except so far as the same may constitute subject-matter of specific claims.

I claim as my invention—

1. A type-writer frame and carriage shift-frame provided each with two oppositely-inclined, oblique contact-surfaces; the oblique surfaces on the shift-frame being adapted for contact with those on the machine-frame at the end of the throw of the shift-frame. 65

2. A main frame and a carriage shift-frame provided each with two oppositely-inclined, oblique surfaces, the oblique surfaces on the shift-frame being adapted for contact with those on the main frame at the end of the throw of the shift-frame and stop-surfaces on the main frame and shift-frame adapted to positively limit the throw of the shift-frame. 75

3. A type-writing-machine frame and a carriage shift-frame provided one with a tapered block and the other with a plate having a correspondingly-tapered notch, said block and notch being adapted for interfitting contact with each other at the end of the throw of the shift-frame. 80

4. A type-writer frame and a carriage shift-frame provided one with a tapered block and the other with a plate having a tapered notch, said notch and block being adapted 90 for interfitting contact at the end of the throw of the shift-frame, and stops on the main frame and shift-frame adapted to positively limit the movement of the shift-frame at the end of its throw. 95

5. The combination with a type-writer frame provided with a guide-standard, of a shift-frame having a guide-rod engaged with said standard, said guide-rod being provided at opposite sides of the standard with tapered blocks, and the standard being provided with oppositely-facing tapered notches adapted to receive said tapered blocks at opposite ends of the throw of the shift-frame. 105

6. The combination with a type-writer frame provided with a guide-standard, and a stop-standard, of a shift-frame provided with a guide-rod adapted to engage said guide-standard; said guide-rod being provided at opposite sides of the guide-standard with tapered blocks and the guide-standard being provided with tapered notches to receive said blocks at opposite limits of the throw of the shift-frame, said guide-rod being also provided with adjustable stop-shoulders adapted 110 for contact with the stop-standard to positively limit the throw of the shift-frame. 115

In testimony that I claim the foregoing as my invention I affix my signature, in presence of two witnesses, this 30th day of October, A. D. 1905. 120

CHARLES RODERICK.
